US00D939082S

(12) **United States Design Patent** (10) **Patent No.:** **US D939,082 S**
(45) **Date of Patent:** **** Dec. 21, 2021**

(54) **PEDICLE SCREW REMOVAL TOOL**

(71) Applicant: **Orthopedic Renovation Technologies, LLC**, San Antonio, TX (US)

(72) Inventors: **Rene Ortiz**, Helotes, TX (US); **Alejandro Rene Ortiz**, Helotes, TX (US)

(73) Assignee: **ORTHOPEDIC RENOVATION TECHNOLOGIES, LLC**, San Antonio, TX (US)

(**) Term: **15 Years**

(21) Appl. No.: **29/652,389**

(22) Filed: **Jul. 30, 2020**

(51) LOC (13) Cl. **24-02**

(52) U.S. Cl.

USPC **D24/133; D24/171**

(58) **Field of Classification Search**

USPC D24/133, 140, 146, 150, 155, 157, 113, D24/127, 171; D8/308, 315, 316, 318, D8/319, 320

(57) **CLAIM**

The ornamental design for a pedicle screw removal tool, as shown and described.

DESCRIPTION

FIG. 1 is a front perspective view of a pedicle screw removal tool, shown independent of environment for ease of disclosure only;

FIG. 2 is a front elevation view thereof, shown independent of environment for ease of disclosure only;

FIG. 3 is a rear elevation view thereof, shown independent of environment for ease of disclosure only;

FIG. 4 is a right side elevation view thereof, shown independent of environment for ease of disclosure only;

FIG. 5 is a left side elevation view thereof, shown independent of environment for ease of disclosure only;

FIG. 6 is a top plan view thereof, shown independent of environment for ease of disclosure only;

FIG. 7 is a bottom plan view thereof, shown independent of environment for ease of disclosure only; and,

FIG. 8 is a rear perspective view thereof, shown independent of environment for ease of disclosure only.

1 Claim, 4 Drawing Sheets
